UNITED STATES PATENT OFFICE.

EMERY L. WALKER, OF MILWAUKEE, WISCONSIN.

SEALING-MACHINE.

1,346,072.

Specification of Letters Patent.

Patented July 6, 1920.

Application filed July 16, 1919. Serial No. 311,174.

To all whom it may concern:

Be it known that I, EMERY L. WALKER, a citizen of the United States, residing at Milwaukee, in the county of Milwaukee and State of Wisconsin, have invented a certain new and useful Improvement in Sealing-Machines, of which the following is a full, clear, concise, and exact description, reference being had to the accompanying drawings, forming a part of this specification.

My invention relates to sealing machines and more particularly to the type of sealing machines used for sealing the folded flaps of shipping containers. Machines of this character are utilized both for what is known as bottom sealing, such for instance as the machine shown and described in the Reissue Patent to Morton No. 14,267, dated March 6, 1917, or for top sealing as shown 20 for instance in my co-pending application Serial No. 311,170, filed July 16, 1919.

My present invention concerns itself with the addition of means to machines of this nature which serve the purpose of holding 25 a container or box flaps in an intermediate position during the time the operator is applying the adhesive, this intermediate position being such that a further movement of the said flaps brings them into their sealing 30 or container closing position.

For purposes of illustration I have shown herein means of this character as applied to a machine used for top sealing, as its application to other similar machines will be perfectly obvious.

My invention as shown, for instance, in connection with a machine of the top sealing type is set forth in the accompanying drawing, in which—

40 Figure 1 is a front view of a single unit of a machine of this character, and

Fig. 2 is a side view thereof.

The machine in general may have suitable standards such as the standards 10 and 45 cross bars 11 and 12 so as to provide a suitable and rigid framework. An upper platen 13 is carried by the framework and more particularly is mounted in the bracket structure 14 which is secured to the cross-rods 11 and 12. A suitable handle 14 controlling the position of the cam 15 moves the platen 13 upwardly or downwardly against the ac-

tion of the spring 16. The upper platen 13 is adapted to be moved downwardly into sealing position whenever a shipping container 17 is in position and ready to have its flaps 18 and 19 forced into their final sealing position. Rear lugs 20 are illustrative of suitable stop means against which the top portion of the container 17 may be pressed 55 as the plunger 13 is moving downwardly, thus to press the abutting edges of the flaps 18 and 19 tightly together, to effect a thorough closure of the container end. A lower platen 21 shown as swingingly mounted 60 about the shaft 22 supports the container 17 and forms the opposing support to the platen 13 when it is moved into sealing position. The lower platen has a front ridge 23 so that this platen when swung outwardly 65 into the dotted position shown in Fig. 2 may support thereon the folded container which is to have its top end sealed. The upper platen is provided with my improved means 24 which hold the box flap 19 in an intermediate position, as will be readily apparent from the dotted illustration in Fig. 2. As the platen 21 is swung inwardly into the position indicated by full lines in Fig. 2, the finger 24 also assists in forcing the flap 70 19 toward its final position.

In the operation of the device it may be assumed that the platen 21 has been swung into the position indicated by dotted lines in Fig. 2, a filled shipping container 17 is 75 then placed thereon and the box flaps 25 bent downwardly. When inserting the container upon the platen 21, the box flaps 25, as stated, have already been bent inwardly 80 into their sealing position and the box flap 19 bent into its intermediate position as shown in dotted lines in Fig. 2. The fingers 24 then support this box flap 19 in this intermediate position. The box flap 19 being in the position shown in dotted lines in Fig. 2 holds down the two lowermost box flaps 25 so that these box flaps 25 are in position 85 to receive the adhesive without the necessity of having the operator hold these flaps in their closed position, nor is it necessary for 90 the operator manually to hold the flap 19. In other words, the operator takes the filled container, bends the flaps 25 inwardly, bends the flap 19 into the position indicated 95 100

2
by dotted lines in Fig. 2, and then places this container upon the platen 21 when said platen is in the position indicated by dotted lines. The operator can then apply the adhesive to the flaps 25 without being inconvenienced by holding the various box flaps in their positions. It must of course be understood that the box flaps tend to move into their open position, and that merely 5 bending them inwardly will not cause them to remain in their inwardly bent position. The operator having applied the adhesive, bends the box flap 18 downwardly and pushes the platen 21 with the filled container into the position shown in full lines 10 in Fig. 2. Thereupon, the operator actuates the handle 14 in a contra-clockwise direction to force the platen 13 downwardly into sealing position, the cam 15 locks the platen 13 in its lowermost position, and the operator 15 may pass on to another sealing machine and come back to this first machine after the sealing operation has been completed. During the time that the operator is moving 20 the handle 14 downwardly so as to bring the platen 13 into sealing position, he exerts pressure against the upper front edge of the container 17, thereby to force it against the stop 20 and cause the edges of flaps 18 and 25 19 to come tightly together, thus to insure 30 a perfect closure.

It will of course be understood that many modifications may be made without departing from the broad nature of my invention.

35 Having however thus described one form which my invention may take, what I claim as new and desire to secure by Letters Patent is:

1. In a sealing machine of the character 40 described the combination with a pair of platens adapted for box end sealing purposes, the box structure being held in a preparatory position prior to sealing, and means carried by said machine adapted when said box structure is in a preparatory position to hold a box flap in an intermediate position.

2. In a sealing machine of the character 45 described the combination with a pair of platens adapted for box end sealing purposes, the box structure being held in a preparatory position prior to sealing, and means carried by said machine adapted when said box structure is in a preparatory position to hold a box flap in an intermediate position, and direct said flap toward its sealing position when said box structure is moved from its preparatory position to a position in which said platens when operated effect sealing of the box end.

3. In a sealing machine of the character 55 described the combination with a pair of relatively movable platens adapted for box end sealing purposes, the box structure being held in a preparatory position prior to sealing, and means carried by said machine adapted when said box structure is in a preparatory position to hold a box flap in an intermediate position, and direct said flap toward its sealing position when said box structure is moved from its preparatory position to a position in which said platens when operated effect sealing of the box end.

sealing, and means carried by said machine adapted when said box structure is in a preparatory position to hold a box flap in an intermediate position.

4. In a sealing machine of the character 70 described the combination with a pair of relatively movable platens adapted for box end sealing purposes, the box structure being held in a preparatory position prior to sealing, and means carried by said machine 75 adapted when said box structure is in a preparatory position to hold a box flap in an intermediate position, and direct said flap toward its sealing position when said box structure is moved from its preparatory position to a position in which said platens when operated effect sealing of the box end.

5. In a sealing machine of the character 80 described the combination with a pair of platens adapted for box end sealing purposes, the box structure being held in a preparatory position prior to sealing, and a finger carried by said machine adapted when said box structure is in a preparatory position to hold a box flap in an intermediate 85 position.

6. In a sealing machine of the character 90 described the combination with a pair of platens adapted for box end sealing purposes, the box structure being held in a preparatory position prior to sealing, and a finger carried by said machine adapted when said box structure is in a preparatory position to hold a box flap in an intermediate 95 position, and direct said flap toward its sealing position when said box structure is moved from its preparatory position to a position in which said platens when operated effect sealing of the box end.

7. In a sealing machine of the character 100 described the combination with a pair of relatively movable platens adapted for box end sealing purposes, the box structure being held in a preparatory position prior to sealing, and a finger carried by said machine adapted when said box structure is in a preparatory position to hold a box flap in an intermediate 105 position, and direct said flap toward its sealing position when said box structure is moved from its preparatory position to a position in which said platens when operated effect sealing of the box end.

8. In a sealing machine of the character 110 described the combination with a pair of relatively movable platens adapted for box end sealing purposes, the box structure being held in a preparatory position prior to sealing, and a finger carried by said machine adapted when said box structure is in a preparatory position to hold a box flap in an intermediate 115 position, and direct said flap toward its sealing position when said box structure is moved from its preparatory position to a position in which said platens when operated effect sealing of the box end.

9. A sealing machine of the character 120 described comprising an upper platen adapted to be swung out of alignment with the upper platen so that a container may be positioned 125

thereon and a finger carried by and projecting forwardly from, said upper platen for holding one of the box flaps in an intermediate position.

5 10. A top sealing machine of the character described comprising an upper pressing platen and means projecting from one edge

of said platen for holding one of the box flaps in an intermediate position while adhesive is being applied beneath the flap. 10

In witness whereof I hereunto subscribe my name this 2nd day of July, A. D. 1919.

EMERY L. WALKER.
